UNITED STATES PATENT OFFICE.

LOUIS C. HELMCAMP AND EDWIN HOXWORTH, OF WACO, TEXAS.

NON-REFILLABLE BOTTLE.

1,089,216.

Specification of Letters Patent.

Patented Mar. 3, 1914.

Application filed March 14, 1912. Serial No. 683,788.

To all whom it may concern:

Be it known that we, LOUIS C. HELMCAMP and EDWIN HOXWORTH, citizens of the United States, residing at Waco, in the 5 county of McLennan and State of Texas, have invented a new and useful Non-Refillable Bottle, of which the following is a specification.

The invention relates to improvements in 10 non-refillable bottles.

The object of the present invention is to improve the construction of non-refillable bottles, and to provide a simple and efficient device, adapted to constitute a closure plug 15 for a bottle or analogous receptacle, and capable after being applied to the same of permitting the contents of the receptacle to be freely decanted and of effectually preventing a liquid from being surreptitiously 20 introduced into the receptacle.

A further object of the invention is to provide a device of this character, adapted to receive the ordinary stopper or sealing means, and capable when removed from one 25 receptacle of reuse on another receptacle.

With these and other objects in view, the invention consists in the construction and novel combination of parts hereinafter fully described, illustrated in the accompanying 30 drawing, and pointed out in the claim here-
to appended; it being understood that various changes in the form, proportion, size and minor details of construction, within the scope of the claim, may be resorted 35 to without departing from the spirit or sacrificing any of the advantages of the invention.

In the drawing:—Figure 1 is a vertical sectional view of the upper portion of a 40 non-refillable bottle, constructed in accordance with this invention. Fig. 2 is a horizontal sectional view on the line 2—2 of Fig. 1. Fig. 3 is a similar view on the line 3—3 of Fig. 1. Fig. 4 is a reverse plan view of 45 the closure plug. Fig. 5 is a detail view of the cork washer. Fig. 6 is a detail sectional view, illustrating the construction of the automatic locking device. Fig. 7 is an enlarged detail sectional view, illustrating the 50 construction of the upper portion of the valve chamber. Fig. 8 is an enlarged horizontal sectional view of the same.

Like numerals of reference designate corresponding parts in all the figures of the 55 drawing.

In the accompanying drawing in which is illustrated the preferred embodiment of the invention, the closure plug 1 is shown applied to the upper portion of a bottle 2, but it is applicable to various receptacles 60 having a neck. The closure plug, which is designed to be molded or otherwise constructed of glass, or other suitable material, consists of an approximately cylindrical body, forming a valve casing and having a 65 tapered exteriorly threaded lower portion 3, which is screwed into and engages corresponding interior threads 4 of the neck of the bottle 2. The walls of the neck are thickened at the lower end of the threaded 70 portion, and the thickened walls, which constrict the passage of the neck, are provided with a horizontal shoulder 5, forming a seat for a washer 6 of cork, or other suitable material, adapted to form a liquid tight joint 75 to prevent the contents of the bottle from coming in contact with an automatic locking device 7.

The locking device 7 consists of a spring 80 constructed of steel, or other suitable material and provided at its ends with upwardly and downwardly projecting portions 8 and 9. The spring, which is flat, is curved longitudinally to conform to the curvature of the inner and outer faces of the lower 85 portion of the valve casing, and the upwardly extending portion, which constitutes an attaching lug, is cemented or otherwise secured in a socket 10 in the lower edge of the valve casing. The depending or engaging portion 9 is adapted to extend into a recess 11 in the shoulder 5, whereby the valve casing is locked against rotary movement to prevent the same from being unscrewed after being applied to a bottle or 90 other receptacle. The valve casing is also provided in its lower edge with a curved recess 12 in which the body portion of the locking device is adapted to be compressed, and the washer 6 has a slot 13 through which 95 the engaging portion 9 of the locking device projects, and which is of sufficient length to permit a sufficient rotary movement of the valve casing to carry the locking device into engagement with the recess 11. The locking 100 devices are applied to the valve casings before the latter are screwed into the necks of the bottles or other receptacles, and as there is no cement applied to the bottle at the time the same is closed by the plug or 105 110

valve casing, there is no delay as is the case when the closure plug or valve casing is cemented in the neck and the bottles must be left in a drying room twelve hours before they are ready for packing and shipment.

The valve casing is provided with an intermediate corrugated enlargement 14, adapted to be securely gripped by the hand in screwing the valve casing into the neck of a bottle and forming a lower shoulder, which fits against the upper edge of the neck. The valve casing is provided with an interior valve chamber, and it has a valve seat 15 at the lower end thereof, and is provided above the same with a stopper receiving chamber or portion 16, adapted to enable the passage through the valve casing to be closed by an ordinary cork stopper, but any other sealing device or closure, such as a crown seal, screw cap, or faucet, may be employed. The longitudinal opening through the valve casing is constricted at 17 by thickening the walls to provide a shoulder or seat and also to obscure the interior of the valve chamber.

The valve chamber, which receives a ball valve 18, has a lower portion 19 located immediately above the valve seat 15 and having smooth walls and being of approximately the diameter of the ball 18, so that the latter will fit snugly within the lower portion of the valve chamber. At the bottom the lower portion of the valve chamber is concave to fit the ball, and it is cylindrical above the concave bottom portion.

The upper portion of the valve chamber is approximately circular in vertical section and is provided with an annular series of ribs 20, triangular in cross section, and forming intervening grooves or gutters for the passage of the contents of the bottle when the latter is inverted to unseat the ball and permit the liquid to be poured from the bottle. The ribs, which extend upwardly from the smooth walls of the lower portion of the valve chamber, have their upper portions curved inwardly to form a step for the ball to prevent the latter from coming in contact with an approximately horizontal guard 21. The guard 21, which has a slight concavo-convex form, consists of a disk and is imperforate and extends over the upper ends of the ribs and is supported by the same. The imperforate guard, which partially constricts the grooves or gutters between the ribs, is of greater diameter than the constricted portion 17 of the passage and is adapted to prevent an instrument introduced into the valve casing and inserted through the constricted portion 17 of the passage through the neck from reaching the

valve and interfering with the operation thereof.

The ball, which is designed to be constructed of rubber, glass, porcelain, or any other suitable material, is placed in the chamber during the process of manufacturing the valve casing. When the bottle is inverted, the ball rolls forward or outward from the valve seat into the upper or outer portion of the valve chamber and is supported by the longitudinal ribs. The grooves or gutters between the ribs permit a free discharge of the contents of the bottle and provide vents for the entrance of air. After the bottle has been emptied and returned to the bottler, the closure plug may be removed by cutting the neck of the bottle in the plane of the locking device, and it may be used again on another bottle, the reuse of the valve mechanism being practically unlimited.

What is claimed is:—

In a device of the class described, the combination of a receptacle having an interiorly threaded neck and provided with a horizontal shoulder having a recess, a hollow closure plug provided with a passage through it and having exterior screw threads to engage those of the neck of the receptacle, said closure plug being also provided in its lower end with a socket and having a curved recess extending from the socket and arranged substantially concentric with the said passage, an automatic locking spring also curved substantially concentric with the passage of the closure plug and arranged at the curved recess thereof and provided at its ends with upwardly and downwardly projecting portions, the upwardly projecting portion of the spring being secured in the said socket and the downwardly projecting portion engaging the recess of the shoulder of the receptacle to lock the closure plug in the neck, and a washer interposed between the lower end of the closure plug and the shoulder of the receptacle and having a slot through which the downwardly projecting portion of the neck extends, said washer being elastic and forming a liquid tight joint between the plug and the receptacle to prevent the contents of the latter from coming in contact with the locking spring.

In testimony, that we claim the foregoing as our own, we have hereto affixed our signatures in the presence of two witnesses.

LOUIS C. HELMCAMP.
EDWIN HOXWORTH.
